UNITED STATES PATENT OFFICE.

GLENN R. HOFFMAN, OF SPRINGFIELD, ILLINOIS, ASSIGNOR TO HOFFMAN MANUFACTURING COMPANY, OF SPRINGFIELD, ILLINOIS, A CORPORATION OF ILLINOIS.

TRANSMISSION BAND.

Application filed March 19, 1923. Serial No. 626,086.

To all whom it may concern:

Be it known that I, GLENN R. HOFFMAN, a citizen of the United States, residing at Springfield, in the county of Sangamon and State of Illinois, have invented certain new and useful Improvements in Transmission Bands; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to transmission bands, and more particularly to the ears of the bands. It has for its object to provide an ear construction that makes it possible to dispense with the extension of the pedal shaft from one ear to the other of the band as customary more particularly in the slow-speed band of the Ford type of transmission, and to give added strength to the band construction as a whole and also simplify the 20 application of the band to its drum and its removal therefrom as well as its operation in applying and releasing its frictional engagement with its drum. In the Ford transmissions as at present in general use, the 25 low-speed pedal shaft spans the space between the two ears of the band and rests in the notched portions or ends of the ears and it supports the expansion spring which tends to spread the ears apart, a threaded 30 nut being employed for passing inward one of the ears to adjust the band to its drum without drag, and a shoulder on the pedal shaft bears against the other ear to press inward that ear and contract the band on 35 application of power through the pedal of the shaft as familiar to those acquainted with the Ford transmission. Under that construction when the band is to be removed from the drum for relining or other purposes, the pedal shaft has to be shifted through quite a range of movement to permit removal of the expansion spring and separation of the band-ears from the shaft to permit proper manipulation of the band 40 for its removal from its drum. Under this construction it also happens at times that the band becomes worn to such an extent that it is liable to do damage to the drum as well as to itself before its defective condition becomes known.

To overcome and obviate the dangers and disadvantages adverted to, the present invention consists in the features of construction hereinafter particularly described and then sought to be clearly defined by the 45 claims, reference being had to the accompanying drawing forming a part hereof and in which—

Figure 1 is a perspective view of the removable ear of the band formed according to the present invention;

Figure 2 is a like view of the other or usually permanently attached ear;

Figure 3 is a perspective of a band, with 50 one ear detached.

In the drawings the numeral 1 designates the metal strap usually constituting a part of the band, and the lining 2 of woven fabric, or other suitable material, connected one to the other in any of the approved methods 55 commonly employed. The removable ear is designated by the numeral 3, and comprises the shank 4 and out-turned ear 5. This ear instead of being notched as usual to receive the pedal shaft is made solid with a stem 6 60 projecting from one face, and with a socket 7 in its other face to receive the shoulder or lug usually forming a part of the pedal shaft, so that with the shoulder or lug fitting in the socket the ear and band will be 65 prevented from moving out of line. This ear is also preferably formed with a depending lug 8 adapted to fit in a socket or slot 9 formed in the metal strap 1 parallel with the folded end 10 of the band which forms 70 an abutment for the end of the ear to bear against when the ear is locked to the band by headed studs 11 fitting in slots 12 formed in the shank of the ear and the ear is drawn or slid on the band so as to bring the studs into 75 the reduced portions of the slots and the lug 8 of the ear is caused to enter the slot 9 of the strap 1.

The ear 13, which is usually fixed or permanently attached to the transmission 80 band, is formed with a solid out-turned end 14, instead of, as usual, with a notched end, and from one face projects a stem 15 and its opposite face is formed with a socket 16 to receive the end of the threaded adjusting 85 nut (not shown) commonly employed in the Ford type of transmission for adjusting the band to its drum without drag.

Under the construction described the stem 90 6 of the removable ear and stem 15 of the 110

permanent ear receive and support the expansion spring (not shown) which may be of any selected appropriate form to discharge its well known function. The 5 threaded adjusting nut instead of receiving the end of the slow speed pedal shaft as customary will fit in the socket 16 and bear against the upturned end of the ear so as to adjust the band in proper position on its 10 drum: and the pedal shaft instead of lying in a notched end of the ear against which the shoulder or lug of the shaft bears for compression purposes, will terminate with the shoulder usually formed thereon and the 15 shoulder will fit in the socket 7 and bear against the solid upturned ear so that through means of the foot pedal the band will be contracted about its drum for the usual purpose.

20 In this construction the use of the low-speed shaft for connecting the two ears of a low-speed transmission band is dispensed with entirely; and the adjacent ends of the 25 two stems projecting from the ears may be so spaced or distanced from each other when the band is adjusted to its drum that when the band lining becomes much worn or to a certain extent as to be liable to do damage 30 to the face of the drum the ends of the stems will meet or abut one against the other and prevent further contraction of the band and consequent damage to the face of the drum. This construction also lessens liability of 35 breakage of the expansion spring. It also facilitates the installation and removal of the transmission band, and makes possible the easier installation of the bands of the reverse and the brake drums, and results in a saving of time, labor and expense in removal of the bands for repairs to the linings 40

and their reinstallation besides making the parts stronger and simpler in their assemblage and operation.

I have illustrated and described with particularity the preferred details of construction but changes may be made therein and essential features of the invention retained. 45

Having described my invention and set forth its merits what I claim is:

1. A transmission band provided with ears 50 having out-turned ends formed on their adjacent faces with projecting stems adapted to receive an expansion spring, one of the ears being detachable.

2. A transmission band provided with 55 ears having out-turned ends formed on their adjacent faces with projecting stems adapted to receive an expansion spring, said stems being in line one with the other and spaced apart for meeting contact to restrict 60 contraction of the band.

3. A transmission band provided with ears having out-turned ends formed on their adjacent faces with projecting stems 65 adapted to receive an expansion spring, and with means on their other faces adapted to receive band contracting means.

4. A transmission band provided with ears having out-turned ends, one of said ears being removable and having a stem projecting from one face and means on its other face to receive part of a pedal-shaft to contract the band. 70

In testimony whereof I affix my signature in presence of two witnesses.

GLENN R. HOFFMAN.
